ABSTRACT OF THE DISCLOSURE

The useful life of metallic iodide lamps has been relatively short by comparison with that of ordinary mercury vapor lamps. Towards the end of life, luminous efficiency decreases quite rapidly, and the useful life is ended when an inordinate increase in starting and restarting voltage takes place. These disadvantages are related to the diffusion of sodium through the wall of the quartz arc tube and, as a consequence, the appearance of free iodine within the arc tube. The occurrence of these phenomena is prevented by the invention which is characterized in one mode by the introduction into the arc tube of a quantity of silicon, suitably as crushed crystals, and in another mode by the incorporation of silicon in fine powder form into the thoria serving as electron-emissive material on the cathodes, the silicon preventing the migration of sodium through the quartz wall.

BACKGROUND OF THE INVENTION

The present invention relates to high pressure mercury vapor lamps in which metals having low ionization potentials are added in the form of volatile halides in order to obtain the emission of white light; the metals thus introduced in definite proportions are thallium, indium, and sodium.

These lamps comprise a burner or arc tube of silica located within an outer protective jacket of hard glass, generally evacuated, and electrodes each constituted by a tungsten shank on which are wound two superposed layers of tungsten wire, the space between turns being filled with thoria whereof the reduction entails the formation of an emissive film of thorium at the end of the tungsten shank, the equilibrium between the speed with which thorium disappears from the film and the speed with which thorium is produced by reduction depending upon the temperature of the electrode.

Metallic halide lamps have lagged in their commercial development by reason of their relatively short useful lives by comparison with those of ordinary mercury vapor lamps, their utility being limited by an increase in starting and restarting voltage and by a decrease in luminous efficiency.

In the state of the art prior to our invention, even for lamps utilizing iodides of great purity and containing no trace of humidity, the useful life was between 1000 and 2000 hours, the drop in luminous efficiency being as much as 30 to 50%.

Experience has shown that even though very high at the first lighting, the starting voltage drops considerably after a few tens of hours of operation, then climbs again and exceeds its initial value after a few hundred hours, so that the lamp becomes unutilizable because in practice it can no longer be started.

As the starting voltage increases, the extremities of the arc tube become coated with a deposit of tungsten which extends progressively over the entire wall and with a localized spot of thorium iodide which develops until

2

finally a sudden increase in the restarting voltage provokes the extinction of the lamp.

ANALYSIS OF PROBLEM

It has appeared to us that these phenomena are linked to the presence of sodium iodide and that they occur according to a mechanism which will now be explained; it has also appeared to us that it is possible to avoid these phenomena and, by so doing, achieve lamps having long lives even though containing sodium iodide.

5 In the vicinity of the hottest parts of the arc tube wall, the recombination of atoms of iodine and sodium is not total; the sodium not recombined causes a progressive attack of the silica which manifests itself by an alteration of its transparency and a gray veiling. This attack, localized in the hottest regions, results in the formation of sodium silicate and silicate monoxide; so long as the attack is weak, the strength of the arc tube is not diminished.

When the attack has propagated itself throughout the thickness of the quartz, the sodium diffuses through the wall and condenses on the colder portions of the outer protective jacket forming a bright metallic coating, while the arc tube fills with iodine which appears in the form of mercuric iodide upon cooling.

15 The iodine liberated in the arc tube or burner is by reason of its electronegativity the cause of the augmentation of the starting and restarting voltage; it has for effect to destroy the film of thorium on the electrode ends thereby provoking the appearance of thorium iodide spots. Since the equilibrium between the formation and the destruction of the emissive film can only maintain itself by a rise in temperature and an increase in cathode fall, the electrodes sputter tungsten which deposits on the wall. When the reserve of thorium is entirely exhausted, a sudden increase in the restart voltage brings about the extinction of the lamp.

20 It has been observed that the migration of sodium through the quartz occurs more rapidly inasmuch as the temperature of the arc tube wall is higher; when blackening begins to occur, the migration of sodium accelerates for the reason that the temperature of the wall increases as it darkens.

25 From the foregoing observation, it follows that any cause direct or indirect of a rise in temperature of the arc tube wall has for effect to accelerate the migration of sodium and, in consequence, the liberation of iodine.

30 For equal power input, a reduction in the size of the arc tube accelerates the diffusion of sodium on account of the direct increase in temperature of the wall.

35 The use of insufficiently emissive electrodes accelerates diffusion of sodium by reason of the blackening provoked by pulverization or sputtering; similarly, the introduction of iodine in the burner accelerates the diffusion of sodium on account of the blackening which results from the attack of the electrodes.

40 The cumulative action of these causes and effects explains the rapid termination of life of iodide lamps as soon as a reduction in the transparency of the arc tube wall occurs.

45 Means which purpose to increase luminous efficiency by reducing heat losses, such as for instance a higher vacuum in the outer jacket, heat insulation of the ends of the arc tube, or a layer on the outer jacket which reflects infrared rays back onto the arc tube, lead to a reduction in life from the fact that these means increase directly the temperature of the wall; in the same vein, it has been observed that an iodide lamp darkens more rapidly in a fixture than in free air on account of the additional heating of the outer jacket.

50 The introduction of free iodine into the arc tube which has been suggested for avoiding attack of the wall by sodium, produces an effect opposite to that hoped for,

the free iodine accelerating the diffusion of sodium by reason of the blackening due to attack of the electrodes; besides the increase in starting voltage and absorption of light by the wall, the luminous efficacy is reduced by reason of the more rapid recombination of the iodides.

The introduction or the appearance of oxygen in the arc tube facilitates the attack of silica by sodium and for this reason should be avoided.

In an iodide lamp emitting white light, the migration of sodium causes a change in the spectral composition while the liberation of iodine entails a lowering in luminous efficacy.

The present invention has for object to suppress the migration of sodium through the quartz wall and, as a result, the appearance of free iodine in the arc tube or burner. There will thus be obtained a considerable increase in the useful life of iodide lamps by maintaining through thousands of hours of service, the constancy of the starting voltage, of the restarting voltage, of the effective operating voltage, of the electric power absorbed, of the luminous efficacy, and of the spectral composition of the light.

SUMMARY OF INVENTION

The present invention is characterized by the introduction into the arc tube of an appropriate quantity of silicon, suitably as crushed crystals, or by the incorporation into the thoria of the electrodes of an appropriate quantity of silicon, suitably as a fine powder. These two modes of realization of the invention may be used separately or simultaneously.

Conformably to the principles which have led to the elaboration of the present invention, it is important to eliminate in the first place all causes of spots and darkening.

Following a complementary characteristic of the invention, the electrodes should present a large emissivity and the iodides should correspond to the smallest valency of the metals; there must not be any addition of free iodine in any appreciable quantity, but the provision of a controlled small quantity of iodine may facilitate the formation of the lamp when the silicon is introduced into the arc tube in the form of crystals.

The two modes of realization of the invention lead to the same results but by different processes; in the first mode of realization, the increase in emissivity is due primarily to the condensation on the electrodes of a part of the silicon introduced into the arc tube, while in the second mode of realization, the protection of the wall comes primarily from the vaporization of a part of the silicon incorporated into the thoria.

BRIEF DESCRIPTION OF THE DRAWING

In the drawing:

FIG. 1 shows in side view a mercury sodium iodide arc lamp in which the invention is embodied;

FIG. 2 is an enlarged fragmentary cross section of one of the electrodes.

FIG. 1 of the drawing illustrates a high pressure metallic iodide lamp 1 comprising a quartz arc tube 2 enclosed within a vitreous jacket 3, provided with a screw base 4. The arc tube contains an inert starting gas, suitably argon at a low pressure, for instance 25 millimeters of mercury; a quantity of mercury which is entirely vaporized during operation of the lamp with the generation of a pressure in the range of 1 to 15 atmospheres; and a quantity of sodium iodide which is in excess of that vaporized at the operating temperature which should be not less than 500° C. at any place. Lesser quantities of thallous iodide may also be provided in order to improve the spectral quality of the light.

The main electrodes 5, 6 at opposite ends of the arc tube comprise a pair of generally concentric coils or helices of tungsten wire 7, 8, the former being tightly wound around the tungsten shank or inlead 9 and the

latter being screwed on the former as shown in FIG. 2. The inside helix 7 has a greater winding pitch in its middle portion whereby to leave cavities which are filled with an electron-emitting mixture 10 consisting primarily of thoria. An auxiliary starting electrode 11 close to main electrode 5 permits starting at a lower voltage. In order to reduce heat losses, the interenvelope space is evacuated prior to sealing off the outer jacket. Also a heat-reflective coating, indicated by speckling 12, is applied to the ends of the arc tube and the adjacent portions of the seals.

According to the first mode of realization of the invention, a quantity of silicon relatively small by comparison with the sodium iodide is introduced into the arc tube in the form of crushed crystals shown at 13 in FIG. 1 for the purpose of forming a small quantity of silicon iodide and of depositing a film of silicon on the wall.

The provision of a quantity of iodine relatively small by comparison with that of silicon, preferably in the form of mercury iodide, has the advantage of reducing the time of formation of the lamp and of not borrowing iodine from the iodides of thallium and indium, so that it does not entail a possible change in the spectral composition of the light during the initial period of operation of the lamp.

As soon as the silicon iodide has formed and the film of silicon has been deposited, an equilibrium is established on which depends the maintenance of the electrical and photometric characteristics of the lamp.

The iodide of silicon facilitates the recombination of iodine and sodium in the vicinity of the wall, the sodium decomposing the silicon iodide to form sodium iodide and liberate silicon which recombines with the iodine; in addition, the film of silicon constitutes an effective protection of the silica or quartz wall against the aggressive action of the sodium, the formation of silicide of sodium not being possible at the temperature of the wall.

Migration of sodium and liberation of iodine being thus avoided, the relative proportions of the different iodides do not change with time and none of the physical or chemical effects due to the electro-negativity of the iodine can produce themselves; it follows that the starting voltage at each lighting of the lamp, the restarting voltage at each half-cycle of current, the effective operating voltage and the electric power absorbed are maintained constant, as also the luminous efficacy and the spectral composition of the light.

The emissivity of the electrodes is considerably affected by the slightest destruction of the thorium film.

The equilibrium between the speeds of disappearance and of production of thorium is accompanied by a reduction in cathode fall and a decrease in temperature of as much as 300° at the ends of the electrodes, whence follows important reduction in pulverization and vaporization.

The losses at the electrodes being smaller, the luminous efficacy is increased; the consumption of the reserve of thoria being less rapid, the life of the electrodes is considerably augmented.

The silicon may be placed at any place on the wall so that the procedure is useful no matter what the operating position of the lamp; it is nonetheless important to avoid having silicon in contact with a portion of the electrodes at a temperature exceeding 2000° C. in order to avoid the production of fusible tungsten silicide.

The formation of the lamp is accompanied by the appearance of a small spot of thorium silicide in the colder region of the wall; this small spot is characteristic of the use of this procedure.

According to the second mode of realization of the invention, an appropriate quantity of silicon is added to the thoria 10 of the electrodes in the form of a fine powder in order to avoid reduction and, as a consequence increase emissivity.

As before, increase in emissivity is evidenced by a reduction of approximately 300° in the temperature of the extremities of the electrodes.

By reason of the increase in emissivity and reduction in temperature, no darkening tends to be produced on the burner wall; the reduction of thoria by the silicon does not produce any liberation of oxygen which could facilitate the diffusion of sodium.

The addition of powdered silicon to the thoria presents, by comparison with the introduction of crystals of silicon into the burner, the advantage of avoiding the risk of formation of fusible tungsten silicide.

The two modes of realization of the invention can be used in combination with the structure which is the subject matter of the patent application of the assignee herein deposited in France 13th of January 1966 having for title "Apparatus Applicable to Electric Discharge Lamps Containing Metallic Iodides in Saturated Vapor Notably Sodium Iodide," such apparatus having for effect to increase the luminous efficacy of iodide lamps operating vertically without entailing an increase in temperature of the burner wall.

Lamps of 400-watts input realizing the conditions of the invention herein have operated 6000 hours with a luminous efficacy of 95 lumens per watt without modification of color appearing during that time.

By way of example, for a 400-watt lamp, the quantity of silicon utilized does not exceed 10 milligrams in the form of crystals introduced into the arc tube and 2 milligrams in the form of powder added to the thoria of the electrodes.

Since the invention permits an increase in temperature of the wall, its two modes of realization may be used in combination with known means for reducing heat losses, notably those consisting of providing a high vacuum in the outer jacket, providing a heat-reflective coating on the ends of the arc tube, or coating the protective outer jacket with a substance reflecting infrared rays back onto the burner.

If the crystals of silicon surround to a suitable depth the lower electrode of a vertically operating lamp, they produce the same effect of enhancement of the luminous emission of sodium as the apparatus which is the subject matter of the patent application of the assignee previously cited.

The procedure which is the object of the present invention is applicable to lamps containing lithium iodide.

Obviously the two modes of realization of the present invention which have been described are not limitative; all analogous procedures based on the same principles and

leading to the same results, notably those consisting in introducing into the burner a small quantity of silicon iodide or in utilizing an element other than silicon, would likewise come within the scope of the present invention.

What we claim as new and desire to secure by Letters Patent of the United States is:

1. A high pressure arc discharge lamp comprising a quartz envelope containing a filling of mercury, metal halide including sodium iodide, and inert gas at a low pressure, thermionic electrodes sealed into the ends of the envelope comprising a tungsten structure supporting a quantity of thoria, the iodides within said envelope corresponding to the smallest valencies of their metals, and a small quantity of silicon enclosed within said envelope for protecting the quartz wall against attack by sodium.

2. A lamp as in claim 1 wherein the metal halide filling includes besides sodium iodide, thallium iodide and indium iodide.

3. A lamp as in claim 1 wherein the silicon is provided in the form of crystals not in contact with an electrode.

4. A lamp as in claim 1 wherein the silicon is provided in the form of a fine powder admixed with the thoria of the electrodes.

5. A lamp as in claim 1 wherein the arc tube is enclosed in an evacuated outer jacket.

6. A lamp as in claim 5 wherein the ends of the arc tube are provided with a heat-reflecting coating.
